TIE-DOWN DEVICE
Robert E. Jellison, 2355 Comstock St.,
San Diego 11, Calif.
Filed July 29, 1963, Ser. No. 298,817
11 Claims. (Cl. 24—68)

The present invention is a continuation-in-part of my co-pending application Serial No. 42,414 filed July 12, 1960, now abandoned.

The present invention relates to fastening mechanism including a strap and a fastener for the strap. The present invention is particularly useful for strapping or tying down material, such as cargo material, sheet material, bales of straw or hay, etc., and is useful for parachute and seat belts adjustment.

The present invention comprises an element which forms a hitch having a loop, two rods which are arranged substantially parallelly of one another, one of which forms an anchor, a strap having an end anchored to the anchor rod. The strap extends progressively, from the anchored end thereof, about the other rod, herein defined as "a strap binding rod," then rearwardly and through the loop of the hitch; it is then brought forwardly to form, with the rearwardly extending portions, a strap loop; it is then looped about the strap binding rod. The strap is then extended rearwardly to form a hand hold portion. The fastening mechanism also includes means for maintaining the rods in positions in which the surface of that portion of the strap, which is looped about the strap binding rod, is sufficient to prevent slippage between that surface and the surface of the strap binding rod when pulling pressure is applied to the hitch.

In one form of the present invention, I provide a frame having a base which carries the two rods. In one embodiment, the frame is also provided with another hitch and this second hitch is carried by a lever, which when turned moves the second hitch closer to the ring type hitch so as to tighten the strap, and the lever is movable so that the second hitch is moved over center, i.e., to a position through a plane intersecting the pivotal point of the lever and that portion of the frame at which the pull of the strap takes place.

Too, the over center lever is provided with a strap engaging portion by which the strap can be utilized as a hand grip for moving the lever.

In another embodiment, the anchor and strap binding rod are movable relative to one another. In that embodiment the anchor rod includes part of a loop-like element, having a portion which extends substantially parallelly with the anchor rod and is disposed so that it engages the underside of that portion of the strap that extends rearwardly from the strap binding rod and includes a pair of sections which connect the anchor rod with the aforementioned portion. These sections span the strap and engage the strap binding rod on that side thereof which is substantially opposite the side which is engaged by the strap.

Other features and the advantages will be apparent from the following description, reference being had to the accompanying drawings wherein preferred embodiments of the invention are illustrated.

In the drawings:

FIG. 1 is a top plan view of the fastening mechanism;

FIG. 2 is a sectional view taken substantially along line 2—2 of FIG. 1 showing the position of the tightening lever at the time that slack loop can be shortened or lengthened;

FIG. 3 is a view similar to FIG. 2 but showing the lever in the position in which the strap is tightened about the object which is to be tied;

2

FIG. 4 is a view partly in section showing another embodiment of the invention;

FIG. 5 is a view looking in the direction of arrow 5 of FIG. 4; and

5 FIG. 6 is a view partly in section showing a still further embodiment of the invention.

Referring more in detail to the drawings, particularly FIGS. 1, 2 and 3, the mechanism includes a fastener 20, a strap 22 and a loop type hitch 24.

10 The fastener 20 includes a substantially U-shaped frame 26 including a bottom or base 28 and side flanges 30 and 32. These side flanges extend upwardly and are spanned by a front rod or strap binding rod 34 and a rear or anchor rod 36. These rods are arranged parallelly with respect to one another and are suitably attached to the flanges 30 and 32. The frame also carries a lever 40 including side arms 42 and 43. These arms are pivotally connected with the flanges 30 and 32 by pivot pins 44. A hitch, in the form of a rod 46, is fastened to the lever arms 42 and 43 intermediate the ends of the lever arms, and this rod 46 is arranged parallelly with the rods 34 and 36. The outer end of the lever arms 42 and 43 carry a rod 48, and this rod rotatably supports a roller 50.

20 A strap 52 is looped over the run 54 of the ring 24 and a strap 56 is looped over the hitch rod 46. These straps 52 and 56 may be formed of steel and are connected with other straps for tying the material which is to be tied down.

25 The strap 22 is formed of flexible material such as 30 nylon, and one end thereof is in the form of a loop 58. This loop is looped over the anchor rod 36 and then extends forwardly, then over and then under the strap binding rod 34, and this portion is referred to as strap portion 60. The overlap portions forming a loop are 35 sewed to one another as is shown at 62. The loop extends rearwardly under the rod 36 and then the single layer of the strap 22 indicated at 64 extends rearwardly, then under and about, as shown at 66, the front run 68 of the loop type hitch 24. The strap then extends forwardly 40 as at 70 to form, with portions 64 and 62, a strap loop portion 70 extends underneath the anchor rod 36 then, as shown at 72, under and about the rod 34 so as to be interposed between the portion 60 and the rod 34. The strap then extends rearwardly as at 74, then under and 45 about the rod 36, as shown at 76, which portion 76 overlies the loop portion on the rod 36. The strap then extends forwardly as at 78, under and about the roller 50, as shown at 80, and then the free end extends rearwardly as shown at 82 to form a hand hold portion. Obviously, if the lever is omitted, the portion 78 will be 50 extended to the left and it will form the hand hold portion.

55 When there is no tension on the fastening apparatus, that is, when there is no pulling force exerted to the left on the strap 52 and to the right on the strap 56, that portion of the strap indicated at 76 can be pulled to the left or rearwardly and the portion 74 readily slides rearwardly and the portion 70 readily slides forwardly about the rod 34, whereby the slack may be taken up in the loop formed by the portions 64 and 70. Although there 60 is tension on the fastening apparatus, slack may be taken up. Or, the slack can be enlarged under all conditions including fully loaded conditions by merely pulling the portion 70 rearwardly, or to the left, at which time the portion 74 will move to the right over the rod 34. However, when force is exerted on the loop 24 rearwardly 65 or to the left, the portion 60 will bind with the portion 72 at the strap binding rod 34 and prevent relative movement to the rear between the ring 24 and the fastener 20. In other words, the fastener is automatically locked.

70 The anchor rod 36 is so disposed on the frame 26 with respect to the strap binding rod 34 that the frame main-

tains the anchor rod in such position that the surface of that portion of the strap, which is looped about the strap binding rod, is sufficient to prevent slippage between that surface and the strap binding rod when pulling pressure is applied at the strap loop.

The present invention is particularly useful as a tie-down device for cargo in which event the opposite ends of the straps 52 and 56 may be joined, or the opposite ends may be suitably connected to other forms of straps used in the tying down. The present invention is also useful as a belt in which the opposite ends of the straps 52 and 56, which are not shown, are connected with one another. Another use for the present invention is similar to that shown in the Graves Patent No. 2,539,997 issued January 30, 1951.

In any use of the device, the portion 78 of the strap 22 is first pulled to the rear or to the left so as to provide sufficient slack for connecting the straps 52 and 56. After the opposite ends of the straps 52 and 56 are connected as desired, the portion 76 of the strap is pulled rearwardly so as to draw the straps 52, 22 and 56 taut. At this time the rod 46 of the lever 40 will be in its front most position. After the straps 52, 22 and 56 have been pulled taut through pulling on the strap portion 76, the portion 78 is looped underneath the roller 48 and then rearwardly as is shown by the portion 82. The operator will then use the portion 82 of the strap 22 and as a hand grip for pulling the lever 40 rearwardly to further tighten the straps. This pulling will be continued until the rod 46 of the lever 40 is moved in a counterclockwise direction to beyond a dead center position with respect to the axis of the pivots 44 and the center line of pressure of the strap portion 60 on the front rod 34, that is, the rod 46 is moved so that it is disposed below a plane intercepting the pivot axis 44 and the center line of pressure on the rod 34. In this manner the straps are locked in position. The advantage of using the portion 82 as a hand grip lies in the fact that both hands of the operator can be used for tightening the straps, and this is particularly advantageous when heavy cargo is to be strapped in position.

Referring now to the embodiment shown in FIGS. 4 and 5, the anchor rod is shown at 136 and the strap binding rod is shown at 134. The rod 134 forms a direct part, i.e., is formed integrally with a hitch 156. The hitch loop is shown at 124 for the strap loop 64, 66 and 70.

In this embodiment, the anchor rod 136 is part of a loop-like element or, as shown as a part of a ring 130 having a portion 131 which lies parallelly with the anchor rod and engages the underside of the strap portion 64. The anchor rod and portion 131 are connected with one another by sections 133. These sections engage the strap binding rod 134 on that side of rod opposite the side engaged by the strap.

The loop-like element 136 functions as a lever when pulling pressure is applied to the hitches 124 and 156. Pulling pressure will tend to rotate the ring 130 in a clockwise direction (as viewed in FIG. 4) about the strap binding rod 134 as a fulcrum for ring sections 133. However such clockwise movement is limited inasmuch as the portion 131 engages the underside of strap portion 64 and thereby limited in its upward movement. Consequently, pressure is exerted by the ring sections 133 rearwardly or to the right as viewed in FIG. 4. Thus it will be apparent that the pressure exerted by the sections 133 on the strap binding rod increases proportionately with the increase of pulling pressure at the hitches, resulting in proportionate increase of binding pressure between strap portion 72 and strap binding rod 134 and between strap portion 72 and strap portion 60.

Thus the ring maintains the anchor rod in such position that the surface of that portion of the strap, which is looped about the strap binding rod, is sufficient to prevent slippage between that surface and the strap binding rod when pulling pressure is applied at the strap loop.

Here again, by pulling on the handle portion 82 of the

strap, the strap loop 64, 62 and 70 can be shortened to thereby tighten the straps (not shown) which are connected with the hitches. Also the strap loop 64, 62 and 70 can be increased by merely pulling to the left on strap portion 70. In this manner the load is released.

Referring now to the embodiment shown in FIG. 6, it is substantially the same as shown in FIGS. 1, 2 and 3 however, the lever 40 and the parts associated with it are omitted. Too, instead of looping the strap section 72 counterclockwise about the strap binding rod 34, it is looped clockwise about said rod. The actions and results however are the same. The hitch for the frame 26 is shown at 256 connected with rod 246, the latter being connected to the side flange 30.

Thus it will be seen from the foregoing that there has been provided fastening mechanism in which the slack can be readily adjusted, that is, either enlarged or contracted by merely pulling on one or the other portion of the strap. Also it will be observed that the structure is inexpensive and simple to operate.

While the forms of embodiment herein shown and described constitute preferred forms, it is to be understood that other forms may be adopted falling within the scope of the claims that follow.

I claim:

1. In combination, a strap; means forming a loop; and a fastener, said fastener including a frame having a base, an anchor rod and a second rod, said rods being arranged substantially parallelly and each having opposite ends supported by the base; means anchoring one end of the strap to the anchor rod, said strap extending progressively from said anchored end over the second rod, and under the second rod, then rearwardly and under the anchor rod, rearwardly of the anchor rod, upwardly through the loop of said means, forwardly to form a strap loop, under the anchor rod, looped about the second rod, rearwardly and then under the anchor rod to form a hand hold portion.

2. A combination as defined in claim 1, and including a lever; means for pivotally attaching the lever to the frame forwardly of the rods for movement forwardly and rearwardly with respect to the frame; a hitch for a strap carried by the lever, said hitch, when the lever is in its rearmost position, being disposed below a plane intersecting said last mentioned means and the center line of pressure of the strap on the second mentioned rod, said lever being provided with a strap engaging portion disposed a greater distance from said last mentioned means than said hitch.

3. A combination as defined in claim 2, in which the lever is provided with a strap engaging roller disposed a greater distance from said last mentioned means than said hitch and means on the lever for supporting said roller.

4. A combination as defined in claim 1, in which the second mentioned rod is provided with a roller for the strap.

5. In combination, a strap; means forming a loop; and a fastener, said fastener including a frame having a base, an anchor rod and a second rod, said rods being arranged substantially parallelly and each having opposite ends supported by the base; means anchoring one end of the strap to the anchor rod, said strap extending progressively from said anchored end over the second rod, and under the second rod, then rearwardly and under the anchor rod, rearwardly of the anchor rod, upwardly through the loop of said means, forwardly to form a loop, under the anchor rod, under and then over the second rod, rearwardly and then under the anchor rod to form a hand hold portion.

6. A combination as defined in claim 1, characterized to include a hitch connected with the frame.

7. In combination:

(A) Means forming a hitch having a loop;

(B) means forming an anchor rod and a second rod, said rods being arranged substantially parallelly;

(C) a strap, said strap having one end fastened to the anchor rod, said strap extending progressively from said anchored end thereof about and spaced from the second mentioned rod, then rearwardly and through the loop of said means, then forwardly to form a strap loop, then looped about and in engagement with the second mentioned rod, and then rearwardly to form a hand hold portion; and

(D) means for maintaining the anchor rod in such position that the surface of that portion of the strap, which is looped about and is in engagement with the second mentioned rod, is sufficient to prevent slippage between said surface and the second mentioned rod when pulling pressure is applied to the means forming the loop.

8. A combination as defined in claim 7, characterized in that the last mentioned means includes a section fixed to the anchor rod and engages the second mentioned rod in that side thereof which is substantially opposite the side engaged by the strap when pulling pressure is applied to the means forming the loop.

9. A combination as defined in claim 7, characterized in that the last mentioned means includes sections fixed to the anchor rod, said sections spanning the strap and engaging the second mentioned rod at that side thereof which is substantially opposite the side engaged by the

10

15

to include:

(E) A hitch, said second mentioned rod being a part of the last mentioned hitch.

strap when pulling pressure is applied to the means forming the loop.

10. A combination as defined in claim 7, characterized in that the last mentioned means is in the form of a loop-like element having:

- (1) A portion extending substantially parallelly with the anchor rod;
- (2) sections spanning the strap and connecting the anchor rod with said portion, said sections engaging the second mentioned rod at that side thereof which is substantially opposite the side engaged by the strap when pulling pressure is applied to the means forming the loop.

11. A combination as defined in claim 7, characterized

20

25

to include:

(E) A hitch, said second mentioned rod being a part of the last mentioned hitch.
